CLAIM

The ornamental design for a color sorting toy as shown and described.

DESCRIPTION

FIG. 1 is a perspective view of a color sorting toy showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view thereof;

FIG. 10 is an embodiment in which the color sorting toy is in its first presentation status thereof;

FIG. 11 is an embodiment in which the color sorting toy is in its second presentation status thereof; and,

FIG. 12 is an embodiment in which the color sorting toy is in its third presentation status thereof.

The broken lines depict portions of the color sorting toy that form no part of the claimed design.

1 Claim, 12 Drawing Sheets
